UNITED STATES PATENT OFFICE.

GEORG MÖLLER, OF COPENHAGEN, DENMARK.

PARTY-LINE TELEPHONE APPARATUS.

SPECIFICATION forming part of Letters Patent No. 698,307, dated April 22, 1902.

Application filed September 20, 1901. Serial No. 75,677. (No model.)

To all whom it may concern:-

Be it known that I, GEORG MÖLLER, a subject of the King of Denmark, residing at Nørre Frihavnsveg 50^A, Copenhagen, in the Kingdom of Denmark, have invented a new and Improved Party-Line Telephone Apparatus, of which the following is a specification.

My invention relates to improvements in party-line telephone apparatus, the object 10 being to provide a simple arrangement whereby several subscribers are enabled to employ a single line to the central office and whereby such subscribers may be connected either with other subscribers on the same line or 15 with such subscribers whose lines lead to the same central office. The central office connects the calling with the called subscriber, no subscriber being able to connect himself with another or to disturb the connection of 20 a speaking subscriber without the intervention of the central office.

The present arrangement differs from similar apparatus heretofore devised in so far as every subscriber is enabled to communicate 25 directly with the central office without the intervention of a mediate station and in so far as the ordinary substation-battery of every subscriber is used for the purpose of cutting out all other lines, whereby the employment of a special battery is dispensed 30 with.

My improved apparatus comprises, broadly, four relays—to wit, a connecting-relay, a disconnecting-relay, a blocking-relay, and an 35 auxiliary blocking-relay.

Furthermore, my apparatus can be used in conjunction with the telephone devices at present in use without necessitating any change whatever in such devices.

40 The invention will be more fully described hereinafter and the novel features pointed out in the appended claims.

Reference is to be had to the accompanying drawings, forming a part of this specification 45 in which similar characters of reference indicate corresponding parts in all the figures.

Figure 1 is a diagram of the circuits for an ordinary telephone apparatus and for my improved apparatus. Fig. 2 is a side elevation 50 of the disconnecting-relay and a front end view of the connecting-relay. Fig. 3 is a top plan view of the connecting-relay. Fig. 4 is

a side elevation of the upper portion of the connecting-relay and appurtenant parts. Fig. 5 is a detailed view showing an escapement 55 employed for a purpose to be hereinafter described. Fig. 6 is a front end view of the auxiliary blocking-relay. Fig. 7 is a side elevation of the auxiliary blocking-relay, and Fig. 8 is a top plan view of the same. 60

My improved apparatus comprises, as aforesaid, essentially four relays, two of which (the blocking-relay *x* and the auxiliary blocking-relay *y*) are connected by circuits 9 and 8, Fig. 1, with the main line 72 and are energized by current supplied from the central station. For the purpose of energizing the blocking-relay either an alternating or a direct current can be employed. The blocking-relay is so constructed or proportioned that 70 it will be operated by an alternating or direct current having a minimum strength of one milliampere. The auxiliary blocking-relay, on the other hand, can be energized by direct current, having a minimum strength 75 of one milliampere, regardless of the direction of the current; but said relay cannot be operated by an alternating current of less than twenty milliamperes, because the tongue of the relay (to be hereinafter described) has 80 not sufficient time for vibration. The connecting and disconnecting relays *z* and *v* are energized by direct current passing through a local circuit, said current being supplied by the usual substation-battery, as will herein- 85 after more fully appear.

To the right of Fig. 1 the circuits of the usual telephone apparatus are shown, and to the left of Fig. 1 the circuits and apparatus forming the subject of the present invention 90 are represented.

For the purpose of explaining the arrangement and operation of the devices comprising the present invention, let it be assumed that a subscriber rings up the central station. 95 Such ringing up is effected in the usual manner by turning the crank of the magneto 34 and by simultaneously pressing a push-button 1, situated at some convenient place on the booth containing the auxiliary telephone 100 apparatus. The corresponding annunciator-drop at the central station will thereby be actuated in the usual manner. At the same time all other subscribers on the same line

will be cut out by means of the magneto-current flowing through the blocking-relay α . Subscribers who have thus been cut out will be informed by visible signals that the line 5 is "busy." The blocking-relay of the calling subscriber is, however, not influenced by reason of the fact that the lower end of the button 1 glides over the upper portion of the indicator-arm 33 to prevent the blocking-relay 10 from attracting its armature. From the magneto 34 the current passes to the binding-post EK of the ordinary telephone apparatus, which binding-post is connected by an outer circuit 2 with the binding-post EK' of the auxiliary apparatus. From the binding-post EK' 15 the current passes through the circuit 3 to the contact-spring 4 and through the contact 5, against which the spring 6 is pressed by depressing the button 1. Thence the current 20 passes to the spring 6 and through the circuit 7 to the binding-post L" of the auxiliary apparatus, with which the outer circuit is connected. The current returns to the central station by way of the said outer circuit through 25 the annunciator-drop and to the binding-post L' of the auxiliary apparatus through circuits 8 and 9 and contact 10 to circuit 11 through the binding-post TL' of the auxiliary apparatus and through the circuit 12 to the binding- 30 post L of the telephone apparatus. Thence the current passes by way of the circuit 13 to the telephone-hook 14 and through the contact 15, spring 16, and circuit 17 to the other pole of the magneto. Thus the central station is 35 rung up and the other subscribers simultaneously cut off.

The manner in which the subscribers are all cut off will now be described.

The magneto-current generated by the calling subscriber passes through the binding-post L' of the auxiliary apparatus, the circuits 8 and 9, the contact 10, (the path formed by line 11, binding-post TL', &c., not constituting a circuit,) the circuit 18, and the 40 blocking-relay α to the circuit 19, thence through the contact 20 and circuits 21 and 37, the latter of which terminates at the binding-post L" of the auxiliary apparatus and from the said binding-post to the other outer 45 circuit. The blocking-relay α will thereby be caused to attract its armature, whereby contact at 22 will be made and simultaneously contact at 10 interrupted. When contact has been made at the point 22, the current from 50 the substation-battery flowing from the binding-post B of the auxiliary apparatus, (said binding-post being connected by circuit 23 with a positive pole of the substation-battery 73,) will pass through circuit 24, contact 20, 55 circuit 19, the blocking-relay, circuit 18, contact 22, and circuit 25 to the binding-post B' of the auxiliary apparatus, said binding-post being electrically connected by circuit 26 with the negative pole of the substation-battery. 60 The current from the said battery is thereby caused to pass through the blocking-relay to energize the same and cause its armature to

remain in attracted position. Since contact at the point 10 is broken, it follows that the outer circuit is disconnected from the binding-post TL', so that the entire telephone apparatus is cut out from the outer circuit. As the armature of the blocking-relay is attracted the indicator will be moved into the position indicated by dotted lines in Fig. 1, remaining in this position until the armature of the blocking-relay α returns to its normal unattracted position. The calling subscriber has now connected himself with the central station, cut out all other subscribers on the same line, and given a signal to show that the line is busy. None of the cut-out subscribers can now be connected with the calling subscriber, the upper portion of the indicator-arm 33, as indicated by dotted lines, being swung into the path of the button. The contact-point of the button cannot therefore be swung downward, and the spring 6, as a result, cannot be depressed. The central station now places the calling subscriber in communication with the subscriber called. Should the called subscriber be located upon some other line connected at the central station, the two lines are connected at the central station in the usual manner. When the conversation has ended, 95 the subscribers "ring off," as usual, and disconnection is then effected at the central station, precisely in the same manner as in ringing up, by the depression of the button 1 and the turning of the magneto-crank. The button is automatically raised by the spring 6 after each depression. In order to reestablish connection with the cut-off subscribers, the central station will now send a positive impulse from a central-station battery through the 100 binding-post L', circuit 8, auxiliary blocking-relay γ , (which is a polarized relay of high self-induction,) and through the circuits 27, 24, 21, and 37 to the binding-post L" of the auxiliary apparatus. By reason of its peculiar construction the auxiliary blocking-relay 105 will not be energized by the previously-passed magneto-current, but only by the impulse sent from the central station, its tongue being thereby swung out against the contact 28. 110 When contact has thus been made, the substation-battery will influence the disconnecting-relay ν in the manner now to be described. From the positive pole of the said battery the current passes through circuit 23, binding-post B of the auxiliary apparatus, circuits 24 115 21 29, disconnecting-relay ν , circuit 30, contact 28, tongue 31 of the auxiliary blocking-relay γ , circuit 25, binding-post B' of the said auxiliary apparatus, and finally through circuit 26 to the negative pole of the substation-battery to attract the armature of the disconnecting-relay. The armature of the disconnecting-relay ν having been attracted contact at the point 20 will be broken by 120 means of the rod 32, connected with the said armature. The rod 32 carries a clamp 75, Figs. 2 and 4, for an arm 76, serving to press the contact 20 against the disk 39. Pressure 125 130

on the contact 20 is relieved immediately upon moving the rod 32, together with the clamp and the arm. By this breaking of the contact the current passing from the substation-battery through the blocking-relay is cut off, whereby the armature of the said relay will be released, contact at the point 10 will again be made, the indicator will disappear from behind the glass disk, and connection will be again established.

In calling up a subscriber the central station will proceed as follows: A direct current will be sent from the negative pole into the circuit leading to the binding-posts L', situated on the booths of all auxiliary apparatus on the line of the called subscriber. The current passes from the binding-post L' through circuit 8, auxiliary blocking-relay y, circuits 27 24 21 37, to the binding-post L'', 20 and to the positive pole of the battery at the central station. The auxiliary blocking-relays are all energized, whereby contact is established at the point 36. The circuits through the substation-batteries will then be closed by the making of these contacts through the medium of the connecting-relays, the current passing from the positive pole of the substation-battery through circuit 23, binding-post B, circuit 24, circuit 21, 30 connecting-relay z, circuit 38, contact 36, tongue 31, circuit 25, binding-post B', and circuit 26 to the negative pole of the substation-battery. The relay v will not be energized unless the tongue 31, under the influence of the current, moves to make contact at the point 28. The connecting-relays z will now attract their armatures, the ratchet-wheels 49 rotating through the distance of one tooth for each impulse sent from the central station. Said disk 49 is rigidly connected with the disk 39, the position of which determines the numbers of the subscribers. In Figs. 1 and 4 the telephone apparatus of subscriber No. 4 is represented. The stop 40 and the notch 41 in the periphery of the disk 39 will operate in the following manner after the ratchet 49 has been moved forward by four teeth: The stop 40 presses upon the stop 42, whereby the spring is pressed against 50 the screw 77 in such a manner that contact 43 is closed, whereby the central station is enabled to energize the bell. The notch 41 will lie opposite the stop 40. By reason of the tension of the contact-spring the stop 44 will fall into the said notch, whereby contact 20 will be broken, the spring no longer engaging the contact-screw.

This arrangement is particularly shown in Figs. 2 to 5. The contact-disk 39 is mounted 60 on the same shaft as a ratchet 49, located above the connecting-relay z. The armature of said relay is provided at its upper portion with a fork 50, Fig. 5, mounted to turn on the armature. When the armature of the connecting-relay is influenced, the fork will move in the direction of the arrow 51, Fig. 5, so that the pallet 52 will engage the teeth

of the ratchet 49 and will rotate the said ratchet by the distance of one-half a tooth, the oppositely-situated pallet 53 being simultaneously disengaged from the ratchet. By reason of the retrograde movement of the armature the pallet 53 is again caused to engage the ratchet, but this time above the next tooth, so that the ratchet is again turned through the distance of one-half a tooth. For every impulse sent from the central-station battery the connecting-relay will be energized to a degree corresponding to a certain part of an entire revolution of the ratchet. 70 When the disconnecting-relay v attracts its armature, the rod 32, Figs. 2 and 4, will cause the fork to assume the position shown in dotted lines, so that the pallet 53 will be disengaged from the ratchet 49 and so that the ratchet, together with the contact-disk, will be returned by the coiled spring 54 to its initial position.

If the central station should, for example, call up subscriber No. 4, four direct-current impulses will be sent through the circuits previously designated. The contact 43, Figs. 1 and 4, will thereby be closed and contact 20 of the apparatus of subscriber No. 4 will be broken, while the opposite effect will be produced at the apparatus of the other subscribers wherever these two contacts are in their initial positions, although the ratchet-wheels have turned, (the notches 41 not being opposed to the stops 44,) whereby said apparatus will be blocked or cut off when the impulses are sent out by the central station. Said blocking or cutting off is effected precisely in the same manner as hereinbefore described. By closing the contact at the point 43 the bell 35 of subscriber No. 4 will be electrically connected with the outer circuit in such a manner that when an alternating current is sent through the circuit from the central station it flows through the following circuit and rings the bell: The alternating current flows through the outer circuit to the binding-post L', circuits 8 and 9, contact 10, (connected with circuit 9,) the armature of the relay x, circuit 11, binding-post T L', circuit 12, binding-post L of the telephone apparatus, circuit 13, telephone-receiver hook 14, contact 15, spring 16, contact 17, short-circuit contact 45 of the magneto 34 and the bell 35, binding-post EK of the ordinary apparatus, circuit 46, a resistance 47 of one thousand ohms, circuit 48, contact 43, circuits 21, and the binding-post L'' of the auxiliary apparatus, and thus back to the central station. Since the resistance of the bell is 125 about three hundred ohms and the resistances of the relay x and the relays y are respectively fifteen hundred and two thousand ohms, and since the bell is connected in parallel with the latter relay, the aforesaid resistance of 130 one thousand ohms serves to produce an electrical balance. If, therefore, the bell resistance were greater, the resistance of one thousand ohms could be correspondingly dimin-

ished. It is evident that when the contact 20 of the apparatus of subscriber No. 4 is broken the blocking-relay x cannot close the circuit from the substation-battery and that the contact 10 of the said apparatus cannot be broken.

If a subscriber wishes to converse with a subscriber not on the same line, but on a line leading to the same central station, and for 10 this purpose rings up the central station, he must hold the button 1 in depressed position until a current is sent through the circuit of the called subscriber in order to operate the proper apparatus in ringing up the called 15 subscriber. When the called subscriber has been rung up, the calling subscriber is automatically notified thereof by the simultaneous ringing of his bell. Not until his bell has ceased to ring may the calling subscriber release the button 1.

In Figs. 6, 7, and 8 the auxiliary blocking-relay hereinbefore mentioned is pictured in detail. Said relay is a polarized relay and, like the blocking-relay, is surrounded with a 25 thick iron jacket in order to increase the self-induction. The relay y is a horseshoe-magnet provided with a winding. The post 65 carries the armature 66 and serves as a support for the magnets 67 and 68. It is a peculiarity of this armature that in its 30 construction two springs 69 70 are so balanced that the tongue 31, secured to the armature 66, can be held between the contacts 28 and 36. It is evident that if a direct current is 35 sent through these relays one of the contacts at the points 28 36, depending upon direction of the current, will be made by means of the tongue 31, while, on the other hand,

contact cannot be made through the influence of an alternating current. When the 40 relays are not energized, no contact is made. In order to render this relay still less sensitive to an alternating current and in order still further to increase the self-induction, the magnetic circuit is closed through the cross- 45 piece 71.

Having thus described my invention, I claim as new and desire to secure by Letters Patent—

1. A party-line telephone apparatus, comprising connecting - relays for establishing talking-circuits between the stations, disconnecting-relays for disestablishing said circuits, blocking-relays for cutting out divers stations from said circuits, and auxiliary 55 blocking-relays for cutting other stations into said circuits.

2. A party-line telephone apparatus, comprising connecting - relays for establishing talking-circuits between stations, disconnecting-relays for disestablishing said circuits, blocking-relays for cutting out divers other stations from said circuits, auxiliary blocking-relays for cutting said divers other stations into said circuits, and means controllable at will whereby a calling subscriber can simultaneously render his own blocking-relay 65 inactive and give warning to divers stations that the line is busy.

In witness whereof I have hereunto set my 70 hand in presence of two witnesses.

GEORG MÖLLER.
